UNITED STATES PATENT OFFICE.

RICHARD E. ELLIS, OF SYRACUSE, NEW YORK, ASSIGNOR OF TWO-THIRDS TO GEORGE N. KUNTZSCH, OF SAME PLACE, AND THOMAS W. MEACHEM, OF ONONDAGA, NEW YORK.

MACHINE FOR TREATING LEAF-TOBACCO.

SPECIFICATION forming part of Letters Patent No. 339,089, dated March 30, 1886.

Application filed October 10, 1884. Serial No. 145,136. (No model.)

To all whom it may concern:

Be it known that I, RICHARD E. ELLIS, of Syracuse, in the county of Onondaga, in the State of New York, have invented new and useful Improvements in Machines for Treating Leaf-Tobacco, of which the following, taken in connection with the accompanying drawings, is a full, clear, and exact description.

This invention consists in a novel construction of a machine designed for crushing and puncturing the stems of leaves of tobacco, so as to render them sufficiently thin, soft, and pliable to be worked with the leaves into cigars, thus accomplishing a great saving of material in the manufacture of cigars.

In the annexed drawings, Figure I illustrates an end elevation of the machine designed for treating tobacco-leaves as aforesaid. Fig. II is a side view of the main parts of said machine. Fig. III is a vertical transverse section on line $\alpha\alpha$, Fig. II. Fig. IV is a detached side view of the lower crushing or compressing roller. Fig. V is a detached plan view of the scraper used in connection with the aforesaid roller. Fig. VI shows enlarged detached views of the puncturing-knives. Fig. VII is an enlarged detached side view of a portion of the central section of the lower roller, showing more fully the seats for the knives. Fig. VIII is a longitudinal section of the cutting-roller.

Similar letters of reference indicate corresponding parts.

P P represent two pedestals or standards rising from a bed-plate, P', and together constituting the supporting-frame of the machine, said frame being mounted on a suitable table or stand, to the foot of which is connected a treadle, T, similar to that of a sewing-machine.

R R' are two cylinders or rollers, arranged parallel one above the other between the two pedestals P P, in which the ends of said rollers are journaled, the upper roller, R, being yieldingly held in its position to the lower roller, R', by the journal-boxes e of the upper roller being seated movably in vertical slots f in the pedestals and supported by springs g, placed under and over the boxes e, as shown in Fig. I of the drawings. Set-screws h, inserted through the top of the pedestals and

bearing on plates placed on top of the upper springs, serve to hold the roller R yieldingly toward the roller R'. The two rollers R R' are rotated synchronously and in opposite directions by a balance-wheel, W, connected with 55 the treadle T by a pitman, D. A pinion, i, on the balance-wheel shaft meshes in a spur-wheel, l, affixed to the journal of the lower roller, R', at one end of the machine, and two intermeshing gears, m m, of equal diameters, 60 attached to the journals of the two rollers at the opposite ends of the machine, transmit motion from the lower to the upper roller. The lower roller, R', I provide with a circumferential row of knives, a a, which I secure in position by dividing the said roller transversely into three sections and providing the central section thereof with radial slots b b, as best seen in Fig. VII of the drawings, into which slots I set the knives a a, fitted closely therein 7c so as to be retained by frictional hold, and projecting slightly from the periphery of the roller. The abutment of the two end sections of the roller against the side edges of the knives serves to sustain said knives laterally. The 75 three sections of the roller R' are of equal diameters, so as to cause the end sections thereof to carry the leaf while the stem of the leaf passes over the knives of the central section. Said roller-sections are keyed on the shaft, as 80 shown, and are thus compelled to rotate together.

B represents an annular band of greater diameter than the lower roller, R', on the central section of which it is hung, said band being 85 provided with a series of transverse slots, through which the correspondingly-disposed projecting knives a a protrude.

c and c' denote two scraper-blades, pivoted to the inner sides of the pedestals P P, and 90 held with their free edges against the rollers by springs S S, as shown in Fig. III of the drawings. The scraper-blade c', which is held in contact with the lower roller, R', is provided with a notch, d, for the passage of the band B. 95 The front of the frame is provided with a shelf, n, on which to lay the tobacco-leaves in position for passing them between the two rollers R R'.

In treating the tobacco-leaves the rollers are 100

rotated by operating the treadle T. The leaves are then introduced between the aforesaid rollers in such a manner as to cause the stems of the leaves to pass their entire length between the band B and upper roller, R, by the impingement of which the stems are crushed and flattened, and at the same time punctured by the projections of the knives a a through the slots of the band. The stems are thus made thin and pliable sufficiently to permit of their being worked with the leaves into cigars. In the aforesaid operation, the band B being of greater diameter than the roller R', said band pushes the crushed and punctured tobacco-stems off from the knives as rapidly as the tobacco-leaves emerge from between the rollers, and the scraper-blades c and c' prevent the rollers and ring B from gumming up.

Having described my invention, what I claim as new, and desire to secure by Letters Patent, is—

1. In combination with the roller R', provided with a circumferential row of knives, a a, and the annular clearing-band, B hung on said roller, the roller R, arranged in proximity

to the roller R', to press the tobacco-stem against the knives a a, substantially as set forth.

2. The roller R', composed of three sections of equal diameters, the central section thereof provided with a circumferential row of transverse slots, b b, and the knives a a set into said slots and held by the frictional hold therein and by the abutment of the end sections of the roller against the side edges of the knives, substantially as described and shown.

3. In combination with the rollers R R', knives a a, and slotted band B, the scraper c, held against the upper roller, and the scraper c', held against the lower roller, R', and band B, and provided with the notch d, substantially as and for the purpose set forth.

In testimony whereof I have hereunto signed my name and affixed my seal, in the presence of two attesting witnesses, at Syracuse, in the county of Onondaga, in the State of New York, this 10th day of September, 1884.

RICHARD E. ELLIS. [L. S.]
